UNITED STATES PATENT OFFICE.

ELLSWORTH E. FLORA AND ROBERT J. ZORGE, OF CHICAGO, ILLINOIS, ASSIGNEES TO ZORGE
SAFETY RAILWAY EQUIPMENT COMPANY, A CORPORATION OF ILLINOIS.

ALARM-SIGNAL MECHANISM.

No. 890,849.

Specification of Letters Patent.

Patented June 9, 1908.

Application filed June 19, 1907. Serial No. 379,791.

To all whom it may concern:

Be it known that we, ELLSWORTH E. FLORA and ROBERT J. ZORGE, citizens of the United States, residing at Chicago, in the county of Cook and State of Illinois, have invented a new and useful Improvement in Alarm Signal Mechanism, of which the following is a specification.

This invention relates particularly to means for giving warning to an engineer, or motorman, approaching an open switch, or an open draw, with his train, or car; and the primary object of the invention is to provide improved apparatus involving the use of a device which will be preparatorily set when the switch is thrown open and which will operate to detonate a torpedo, or explosive body, when a train passes over it approaching a switch.

The present invention constitutes an improvement upon the apparatus described and generically claimed in our allowed application No. 330,411, filed October 11th, 1906.

The invention is illustrated in the accompanying drawings, in which:—

Figure 1 represents a diagrammatic view of a portion of a railway track equipped with this improved alarm device; Fig. 2, a sectional view taken as indicated at line 2 of Figs. 1 and 4, and showing details of torpedo-placing mechanism of improved construction; Fig. 3, a sectional view taken as indicated at line 3 of Fig. 2; Fig. 4 a plan sectional view taken as indicated at line 4, Fig. 3; Fig. 5, a plan view of the mechanism shown in Fig. 2, with the lid of the casing shown in said figure removed; Fig. 6, a diagrammatic view illustrating the circuits of an electric motor, a magnet controlling an ejector arm, a magnet controlling the motor circuit, and a shunt circuit for the motor employed for reducing the operative current supplied to the motor an instant before the motor is brought to a stop; Fig. 7, a broken bottom view of the rotary disk or torpedo carrier employed; Fig. 8, an enlarged broken sectional view of the torpedo carrier and one of the reciprocable torpedo holders or slides employed, the section being taken as indicated at line 8 of Fig. 5; Fig. 9, a broken sectional view taken as indicated at line 9 of Fig. 2, and illustrating details of the ejector arm and its rock shaft; Fig. 10, a section taken as indicated at line 10 of Fig. 4, and showing details of a connection between the

actuating arm of said rock shaft and a gear of the gear train actuated by the electric motor, said connection comprising telescoping members and an electro-magnet which serves, when energized, to couple the telescoping members together, so that they will move as a unit in the operation of retracting a torpedo holder or slide; Fig. 11, a broken section taken as indicated at line 11 of Fig. 2, and showing a detail of the connection between one of the telescoping members mentioned above and the armature of the corresponding electromagnet; and Fig. 12, a view taken as indicated at line 12 of Fig. 6, and showing a detail of the automatically-controlled switch of the motor circuit.

It may be preliminarily stated that in the diagram illustrated in Fig. 1, the rotary torpedo carrier is represented as controlled by an electric circuit which is controlled by a branch circuit connected with the switch-point of the railway track, and is further controlled by two electric circuits connected with two insulated sections of the railway track. The torpedo-placing device is arranged to operate to place a torpedo beneath a train approaching the switch-point in the event that the branch circuit is interrupted at the switch-point, and the torpedo-placing device will not operate to place a torpedo beneath a train passing in the opposite direction, that is, away from the switch-point, unless the electric circuit connected with the intermediate insulated track section, shown in Fig. 1, is broken. In the operation of placing a torpedo upon the track, when the controlling circuit of the torpedo-placing mechanism is broken, as happens when a train approaches the open switch, the mechanism operates to thrust one of the radially-movable torpedo holders outwardly and thereby locate a torpedo above the adjacent track rail, and when the controlling circuit is restored, the mechanism operates to withdraw the projected torpedo holder. In the event that the torpedo is exploded before the withdrawal of the torpedo holder, the holder makes a complete inward movement and thereupon the mechanism operates to revolve the torpedo carrier one step to bring a fresh torpedo into alignment with the opening in the casing. In the event the torpedo is not discharged before withdrawal, the torpedo holder makes an incomplete inward movement and the clutch device which con-

trols the rotary movement of the torpedo carrier is not operated to cause the torpedo carrier to rotate. The ejector arm is normally actuated by a weight when the controlling circuit is broken and the ejector-holding magnet is deenergized, and at the instant the circuit of said magnet is broken the circuit of the internal magnet which controls the motor circuit is broken, permitting the 10 switch of the motor circuit to be actuated under the force of the weight with which it is equipped, thereby establishing the motor circuit, and the motor thereupon operates to cause the ejector-controlling magnet to follow its armature so as to be in readiness to 15 retract said armature when the controlling circuit is reestablished.

In the preferred construction, A represents a railway track electrically divided into sections A¹, A², A³, the section A¹ having connected therewith a side-track A⁴ and a switch-point A⁵ operated by any convenient means (not shown); B, torpedo-placing mechanism controlled by a circuit B¹, having 20 a branch B² adapted to be broken when the switch-point A⁵ is open to admit a train to the side-track, and having a branch B³ controlled by circuits connected with the track; B⁴, an electric circuit connected with the 25 track section A³ and controlling the branch B³ of the circuit B¹; B⁵ an electric circuit connected with the track section A² and serving, in connection with the circuit B⁴, to control the branch B³ of the circuit B¹; and C a 30 visual signal, which, in connection with the alarm or detonating signal B is controlled by the circuit B¹. It may be stated here that the circuit B⁴ has in it a magnet whose armature controls a circuit breaker with which the 35 circuit B¹ is equipped, and the circuit B⁵ has in it a magnet which has two armatures, one of which serves as a lock for said first-named armature and the other of which serves as a lock for its companion armature. Also, the 40 circuit B⁵ is provided at different points with batteries or generators, one of which is adapted to be short-circuited by a train, thereby partially deenergizing the magnet in the circuit and permitting that armature of said 45 magnet which is most easily released to fall back into position to lock the armature of the magnet in the circuit B⁴, while it is itself sustained by its companion locking-armature. The visual signal is controlled from the 50 circuit B¹ through the medium of a relay, and the torpedo-placing device is controlled through the medium of the visual signal and an additional relay.

The device B comprises a casing having a 55 lower portion b of substantially rectangular form and adapted to fit between ties b¹, and having an upper portion b² of circular form equipped with flanges b³ adapted to be supported on the ties; a swinging casing-top b⁴ adapted to be thrown back to permit access

to the interior of the casing; a pivoted disk or plate b⁵ within the upper portion of the casing and between which and the casing top is a carrier chamber b⁶; a rotary carrier b⁷ equipped centrally with a stud b⁸ journaled 70 in a bearing b⁹, with which the disk b⁵ is provided centrally; radially slidable torpedo-carrying members b¹⁰, connected with the carrier b⁷; suitably spaced frame plates b¹¹ (Figs. 3 and 4), connected by bolts b¹² with 75 flanges b¹³ with which the under surface of the disk b⁵ is equipped, said plates b¹¹ depending into the lower portion b of the casing and serving to support the gear train and other movable parts of the mechanism; a slide-actuating rock-arm, b¹⁴ having its lower end journaled on a rock-shaft b¹⁵ (Figs. 2 and 9) and actuated through the medium of a bifurcated member b¹⁶ rigidly connected with the shaft b¹⁵; an actuating arm b¹⁷ for the 80 rock-shaft b¹⁵ connected by a magnet-equipped telescopic connecting member b¹⁸ with a wrist-pin b¹⁹ on a segmental gear b²⁰; a shaft b²¹ on which the segmental gear b²⁰ is secured, said shaft being actuated by a gear 85 b²² meshing with a gear b²³ secured on a shaft b²⁴, which is equipped with a worm wheel b²⁵; an electric motor b²⁶ having a shaft equipped with a worm b²⁷ which actuates the worm wheel b²⁵; a shaft b²⁸ equipped with a gear 90 b²⁹ actuated by the segmental gear b²⁰; a bevel gear, b³⁰ on the shaft b²⁸ and meshing with a bevel gear b³¹ loosely journaled on a vertical shaft b³² and equipped with a clutch member b³³; a companion clutch member b³⁴ 95 splined on the shaft b³²; a bell-crank clutch-shifting lever b³⁵ supported on a pivot b³⁶ carried by a bracket b³⁷ depending from the plate b⁵; an actuating rod b³⁸ connected with said bell-crank lever and movable in a guide 100 b³⁹; a crank b⁴⁰ secured on the upper end of the shaft b³² and serving to actuate the rotary torpedo carrier; a weight b⁴¹ rigidly connected with the rock-shaft b¹⁵ and tending to 105 rotate said shaft in the direction indicated by the arrow in Fig. 2; a circuit-controlling disk b⁴² fixed on the shaft b²⁴ and controlling the circuit of the electric motor b²⁶; a switch or circuit-controlling member b⁴³ co-acting with the circuit-controlling disk b⁴² and serving 110 also as the armature of an electro-magnet b⁴⁴; and an electro-magnet b⁴⁵ fixedly connected with one of the telescoping members of the connecting rod b¹⁸ and serving to hold 115 said telescoping members in the collapsed condition shown in Fig. 2 while the circuit of said magnet is maintained.

The casing b may be of any suitable form, but it is preferably of the form illustrated. It is equipped above one of the flanges b³ with 120 pivot lugs b⁴⁶ for attachment of the cover b⁴, and is equipped above the other one of the flanges b³ with securing-lugs b⁴⁷, whereat the free or swinging edge of the cover may be secured as by means of the member b⁴⁸ shown 125

in Fig. 3. The inner casing-plate b^5 is equipped with pivot lugs b^{49} supported on a pivot b^{50} as shown in Fig. 2, said pivot being suitably supported by the casing.

5 The free edge of the plate b^5 rests upon a support b^{51} as shown in Fig. 2. The mechanism is carried by the plate b^5 and the plates b^{11} depending therefrom, so that when the plate b^5 is swung upon its pivot, as may be accomplished by a handle b^{52} , the mechanism will be swung out of the casing and subject to inspection. This may be accomplished by first removing the rotary carrier b^7 . The inner casing-plate b^5 is equipped centrally on its upper surface with a ring-shaped flange b^{53} as shown in Fig. 2, and the said flange is provided on the side towards the opening b^{54} with a slot b^{55} which registers with a radial slot b^{56} with which the plate b^5 is provided, 10 and in which the upper portion of the slide-actuating arm b^{14} works. The rotary carrier b^7 may be of any suitable construction. As shown, it comprises a disk equipped with projecting arms b^{57} , and it has radial recesses 15 or guides b^{58} on its upper surface which receive the slidable torpedo holders b^{10} . The bottoms of the recesses or guides b^{58} are provided with radial slots b^{59} .

As shown in Fig. 7 the under side of the 30 carrier is equipped with radial flanges b^{60} joined at their inner ends by curved portions b^{61} , thus affording cam-surfaces adapted to be engaged by the crank b^{40} on the shaft b^{32} , for the purpose of actuating the carrier. Each 35 radially-movable slide b^{10} comprises a shank equipped at its inner end with a depending lug b^{62} adapted to be engaged by the bifurcated head of the rock-arm b^{14} . Said lugs b^{62} work normally within the ring b^{53} during 40 the rotation of the carrier. The outer end of each torpedo holder is equipped with lateral lugs b^{63} which normally rest upon the flanges b^{64} flanking the recesses b^{58} of the torpedo carrier, and when the torpedo holder is thrust 45 outwardly, said lugs, riding off the ends of the flanges b^{64} , permit the outer end of the torpedo holder to drop slightly, so that the lugs b^{63} are in position to engage the outer ends of the flanges b^{64} and prevent completion 50 of the inward movement of retraction of the torpedo holder in the event that the torpedo is not exploded or used. This expedient serves to prevent rotation of the torpedo carrier in a manner to be explained 55 presently. The torpedo holders are equipped at their outer ends with torpedoes b^{65} and the shanks of the torpedoes are weakened adjacent to the torpedoes by perforations b^{66} so that the shank will be readily broken when 60 the explosion occurs. The shanks are of cast metal to enable this to be effectively accomplished.

As has been indicated, the slide-actuating arm b^{14} is actuated by the member b^{16} , which 65 is rigidly mounted upon the rock-shaft b^{15} ,

the slide-actuating arm being loosely mounted upon said shaft to permit a certain amount of idle movement of the member b^{16} before the arm b^{14} is actuated. The member b^{16} is provided at its upper end with two laterally-projecting lugs or stops b^{67} , b^{68} , (Figs. 2 and 9) adapted to engage the arm b^{14} . A spring b^{69} tends to hold the arm b^{14} in engagement with the stop b^{67} . In the normal position, before reciprocation of a torpedo 75 holder has occurred, the upper end of the arm b^{14} bears against the inner end of the slot b^{56} .

As shown in the right hand portion of Fig. 2, however, the torpedo holder has been actuated and then incompletely retracted, the lugs b^{63} having engaged the outer ends of the flanges b^{64} , thus arresting the retraction of the torpedo holder. In returning to the normal position shown in Fig. 2, the wrist-pin b^{19} on the mutilated gear b^{20} rocked the member b^{16} farther to the left than it is represented in Fig. 2, and then returned it to the position which it occupies in Fig. 2, the spring b^{69} yielding to permit this movement while the 80 rock-arm b^{14} remained stationary. The slide-actuating rock-arm b^{14} comprises as shown in Fig. 9, two telescoping sections, one of which is pivotally connected with the rock shaft b^{15} and the other of which is pivotally 85 connected with a slide b^{70} supported on the horizontally-disposed guide rod b^{71} . The slide b^{70} is equipped with an arm b^{72} which serves to actuate the rod b^{38} and thereby throw the clutch member b^{34} into engagement with clutch member b^{33} when the rock arm b^{14} returns to the extreme inner end of its traverse. Thus, rotation of the carrier b^7 is provided for only when the slide-actuating 90 arm b^{14} returns to the extreme inner end of 95 its traverse.

As has been indicated, the connecting means between the arm b^{17} which actuates the shaft b^{15} and the wrist-pin b^{19} with which the mutilated gear b^{20} is equipped, comprises 100 telescoping sections. Thus, as shown in Fig. 10 there is a sleeve b^{73} pivotally connected with the arm b^{17} and a rod b^{74} telescopically-received by said sleeve and connected with a member b^{75} which is journaled on the wrist-pin b^{19} . The member b^{75} carries the electro-magnet b^{45} . The sleeve b^{73} is equipped with a rigidly-connected collar b^{76} , which carries, as shown in Fig. 11, a lug b^{77} which is joined by a bolt b^{78} to the armature b^{79} of the magnet b^{45} . Confined between the lug b^{77} and the armature b^{79} is a spring b^{80} . This connection is designed to permit the armature to adjust itself properly to its poles under all conditions. A positive locking device between the telescoping sections of the connecting rod b^{18} is provided so that it will not be necessary to depend wholly upon the pull of the magnet for retracting the torpedo 115 holder in the event the torpedo holder should 120 125 130

become frozen to the track. This device comprises a pawl b^{81} mounted upon the sleeve b^{73} and adapted to engage the shoulder b^{82} with which the rod b^{74} is provided. A pin or cam b^{83} (Figs. 4 and 10), carried by one of the frame plates b^{11} is so located as to engage the pawl b^{81} and effect a release at the moment the parts reach the position shown in Fig. 2, so that the lower section of the telescopic 10 connecting rod b^{18} will be free and ready to permit actuation of the slide-actuating arm b^{14} under the force of the weight b^{41} when the magnet b^{45} is deenergized.

The mutilated gear b^{20} is provided on one 15 side with a stud b^{84} adapted to engage the arms b^{85} of a triangular member b^{86} carried by the gear b^{29} , thereby aiding in setting the gear b^{29} in motion. The mutilated gear b^{28} is equipped at b^{87} with a sufficient number of 20 teeth to cause a one-third revolution of the gear b^{29} . The gear b^{29} is normally locked against rotation by a pawl b^{88} which is supported on a pivot b^{89} and equipped with a weight b^{90} . The pawl b^{88} has a locking 25 shoulder b^{91} adapted to engage any one of three lateral studs b^{92} with which the gear b^{29} is equipped. Said pawl b^{88} is further provided as shown in Fig. 2 with a cam arm b^{93} adapted to be engaged by a lateral stud b^{94} 30 upon the further side of the mutilated gear b^{20} , as shown in Fig. 2, whereby the locking pawl will be preparatorily disengaged from the gear b^{29} an instant before the stud b^{94} engages one of the arms b^{85} .

35 As shown in Fig. 1, the circuit B^1 is equipped with an electro-magnet 1 and a battery 2. The magnet 1 has an armature 3 controlling the circuit 4 of an electro-magnet 5, the circuit 4 being provided with 40 a battery 6. The magnet 5 serves normally to hold elevated a visual signal, or semaphore, 7 and thus maintain in a normally closed condition an electric circuit 8 having therein a battery 9 and an electro-magnet 10. 45 The magnet 10 has an armature 11 controlling a circuit 12 provided with a battery 13. The circuit 12 is connected with terminals 33 and 34 of the torpedo-placing mechanism, and, as will be presently described, said circuit 50 serves to energize the magnet b^{45} and the magnet b^{44} of the torpedo-placing mechanism. The shank of the visual signal 7 forms a part of the circuit 8 and normally makes contact with the contact point 14 in 55 the circuit.

Both track-rails of the electrically-insulated track section A^3 are connected with a track-battery 15 and the track-rails form a part of the electric circuit B^4 . Said electric 60 circuit is equipped with a magnet 16 provided with an armature 17, on which is mounted a yielding circuit-changer or circuit-breaker 18. The armature 17 is equipped near its extremity with a laterally projecting 65 stud 19 and a spring 20 of adjustable tension

tends to draw the armature away from its magnet and against a stop 21. The track section A^2 is equipped with a track-battery 22 connected with both track rails, and the track-rails form a part of the electric circuit B^5 . The electric circuit B^5 is further provided with a battery 23 and an electromagnet 24. The magnet 24 is provided with an armature 25, which serves as a locking member for the armature 17 when the battery 22 is short-circuited and a stop 26 is provided, which limits the outward movement of the armature 25 in case the circuit B^5 is broken. The magnet 24 is further provided with an armature 27 of bell-crank shape, which is supported on a pivot 28 and equipped at its angle with a hook 29 adapted to engage the stud 30 on the armature 25. The armature 27 is limited in its drop by a stud 31, in the event of the breaking of the circuit B^5 . A 70 spring 32 of adjustable tension is connected with the armature 25 and in the event of the weakening of the current passing through the magnet 24, as by short-circuiting of the battery 22, the armature will be drawn 75 slightly away from the magnet until the stud 30 engages the hook 29, in which condition the upper end of the armature 25 will rest beneath the stud 19 and lock the armature 17, thus preventing breaking of the circuit B^1 if the battery 15 is short-circuited at 80 the same time that the battery 22 is short circuited. 85

Current is supplied to the motor b^{26} from a generator 35 having a circuit 36 connected 90 with terminals 37 and 38 connected with the casing b of the mechanism B. As shown in Fig. 6 the terminals 33 and 34 are also connected with the casing b and the said terminals are joined by conductors 33^a and 34^a to 95 terminals 33^b and 34^b , which are connected with the horizontally-disposed swinging plate b^5 . Likewise the terminals 37 and 38 are connected by conductors 37^a and 38^a with terminals 37^b and 38^b carried by the 100 plate b^5 . This expedient is adopted to permit the mechanism to be swung out of the casing b as above described. From the terminals 33^b and 34^b a branch circuit 39 extends to the magnet b^{45} , and a branch circuit 105 40 extends to the magnet b^{44} . From the terminals 37^b and 38^b a circuit 41 extends to the electric motor b^{26} and includes the circuit-controlling disk b^{42} and the oscillating switch b^{43} , which is controlled by the magnet b^{44} . 110 Connected with the brushes 42 of the motor b^{26} is a shunt circuit 43 having therein a resistance coil 44. The circuit 43 is equipped with yielding contact members 45, 46, one of 115 which has a cam portion 47 adapted to be engaged by cams or studs 48, 49, of insulating material, carried by the gear wheel b^{22} . The function of the shunt circuit 43 is to short-circuit the current passing to the motor an instant before it is desired that the motor 120 125 130

shall stop, so that the speed of the motor will be decreased and the motor will be readily stopped when the contact member b^{43} engages an insulated portion of the disk b^{42} .

5 The relation of the disk b^{42} and the switch b^{43} is shown in Fig. 12. In the illustration given the disk is compound, or comprises two companion disks 50, 51, the former of which is equipped with a block of insulation 52 and the latter of which is equipped with a block of insulation 53. The disks are clamped between a collar 54 and nuts 55 with which the shaft b^{24} is equipped. The angular relation of the insulation blocks, 52, 15 53 may be changed, therefore, at will. The member b^{43} is supported on a pivot 56 and equipped with a weight 56^a. The upper end of the member b^{43} is bifurcated and carries two brushes 57 and 58. The magnet b^{44} 20 normally maintains the brush 58 in contact with the disk and resting against the insulation 53. When the magnet b^{44} is deenergized the weight 56^a tilts the member b^{43} and throws the brush 57 into contact with the 25 metallic portion of the disk, thereby closing the motor circuit.

From the foregoing detailed description, the operation of the apparatus will be readily understood. If the switch-point A⁵ be open, 30 as illustrated in Fig. 1, the branch circuit B² being thereby broken, a train entering the section A³ in the direction indicated by the arrow will deenergize the magnet 16 and permit the armature 17 to be dropped, thereby 35 by breaking the circuit B¹, deenergizing the magnet 1, permitting the visual signal 7 to drop, breaking the circuit 8, deenergizing the magnet 10 and breaking the circuit 12. When the circuit 12 is broken, the magnet 40 b^{45} is deenergized, permitting the weight b^{41} to actuate the ejector arm b^{14} and project a torpedo to a position above the rail. At the same time, the magnet b^{44} is deenergized, permitting the weight 56^a to shift the switch 45 or contact member b^{43} thereby establishing the motor circuit, whereupon the motor operates to turn the wheel b^{20} and cause the magnet b^{45} to follow its armature, the circuit-controlling disk b^{42} being operated at the 50 same time to bring the insulation block 52 beneath the brush 57. An instant before this happens, the shunt circuit 43 of the motor is closed by the cam 49 carried by the gear wheel b^{22} . When the insulation 52 55 passes beneath the brush 57, therefore, the motor stops at once. This occurs after the mutilated gear b^{20} has made one-third of a revolution and the magnet b^{45} has been brought again into engagement with its armature. At the same time the pawl b^{81} 60 engages the shoulder b^{82} with which the upper telescoping member of the rod b^{18} is provided, thereby positively locking the telescoping members of the rod b^{18} together. It should 65 be observed that in the event the weight b^{41}

should, for any reason, be insufficient to wholly project the torpedo, the movement of the magnet b^{45} under the action of the mutilated gear b^{20} insures a completion of the movement of projection of the torpedo when 70 the magnet b^{45} , in its downward stroke, strikes against the armature b^{79} .

Upon a reestablishment of the circuit B¹, as will occur when the switch A⁵ is shifted and the branch circuit B² is established, the 75 circuits 4, 8 and 12 will be reestablished and the magnets b^{44} and b^{45} reenergized. Thereupon, the member b^{43} will be shifted to reestablish the motor circuit and the motor will begin to operate a second time and will 80 continue to operate until the insulation 53 passes beneath the brush 58, the cam 48 of the gear wheel b^{22} operating, in the meantime, to again close the shunt circuit 34 and divert a portion of the current from the 85 motor. It is to be observed, also, that the shunt circuit, since it is closed at the instant when the motor begins operation, acts to prevent a violent starting of the motor.

In the event that the torpedo is not exploded before the motor is set in operation to 90 retract the torpedo holder, the shoulder b^{83} at the extremity of the torpedo holder will engage the outer end of the torpedo holder guide so that the torpedo holder will stop in 95 the position shown in the right hand portion of Fig. 2, the rock-shaft b^{15} being permitted, by the spring b^{69} , to make an idle movement while the gear b^{20} is completing its revolution. In the event that the torpedo is exploded before the torpedo holder is retracted, the outer end of the torpedo holder is 100 destroyed and the ejector arm b^{14} will be permitted to complete its inward movement, in which case the arm b^{72} of the slide b^{70} will 105 strike the rod b^{38} and throw the clutch member b^{34} into engagement with the clutch member b^{33} , whereupon the crank b^{40} will operate to turn the torpedo carrier one step to bring a fresh torpedo into alignment with the opening b^{34} . It should be here observed that the bell-crank lever b^{35} is equipped with a weight 110 59 (Figs. 2 and 4), which tends normally to hold the clutch member b^{34} in the position shown in Fig. 2. As has been stated, the stud b^{83} engages the locking pawl b^{81} an instant before the mutilated gear b^{20} reaches the position shown in Fig. 2 and disengages the locking pawl so that the weight b^{41} will be 115 free to actuate the ejector the instant the circuit of the magnet b^{45} is broken.

In the event that a train passes over the track in a direction opposite to the direction indicated by the arrow in Fig. 1, it is desirable that the torpedo-placing mechanism 120 shall not be operated. Assuming a portion of the train to be in the section A³, the batteries 22 and 15 will be short-circuited. The armature 25 will, therefore, move to a position to engage the stud 19 of the armature 125 130

- 17, the armature 25 being held in this position by the armature 27. Notwithstanding, therefore, the deenergization of the magnet 16, the branch circuit B³ will not be broken.
- 5 Should the circuit B⁵ be broken, however, the armature 27 would drop, thereby permitting the armature 25 to fall back against its stop 26 and allow the armature 17 to drop, thereby causing a torpedo to be placed upon the
- 10 track. An alarm, under such conditions, would serve to indicate a breakage of the circuit B⁵ and the necessity for repairing the same.

It will be evident to those skilled in the art that many or all of the features of the invention herein shown may be usefully employed in connection with block-signals, railway-crossings, at switches to prevent fouling with main line, at curves, tunnels, water-tanks and 20 in fact wherever it is desirable to protect a section of a railway track.

The foregoing detailed description has been given for clearness of understanding only and no undue limitation is to be understood therefrom.

What I regard as new and desire to secure by Letters Patent is:—

1. The combination with a track, of torpedo-placing mechanism comprising a carrier, torpedo holders mounted thereon, and means for projecting the torpedo holders, comprising a magnet-held ejector, and means for actuating the magnet to bring it again into engagement with its armature after the 35 ejector has begun its movement of ejection.

2. In means of the character described, the combination of a rotary carrier, a series of slides mounted thereon, a carrier-actuating member, a slide-actuating member, a magnet controlling the slide-actuating member, a gear train serving to actuate said members and said magnet, an electric motor, and electro-magnetic controlling means for said motor.

45 3. In means of the character described, the combination of a carrier, a series of torpedo holders mounted thereon, a carrier-actuating member, a holder actuating member, an electric motor geared to said members, and electro-magnetic controlling means for said motor.

55 4. In means of the character described, the combination of a carrier, torpedo holders mounted thereon, a carrier-actuating member, a holder actuating member, a gear train serving to actuate said members, an electric motor serving to actuate said gear train, electro-magnetic controlling means for said motor, a clutch controlling the carrier-actuating member, and automatic actuating means for said clutch.

60 5. In means of the character described, the combination of a rotary carrier, a series of torpedo slides mounted thereon, a carrier-actuating member, a slide-actuating member,

means for preventing complete inward movement of a slide after projection thereof in the event of non-explosion of the torpedo, a clutch controlling the carrier-actuating member, clutch operating means controlled by the ejected slide, and means for operating the carrier-actuating member through the medium of said clutch when the clutch is thrown to the operative position.

6. The combination with a railway track, 75 of torpedo-placing mechanism comprising a rotary carrier, radially movable torpedo slides mounted thereon, mechanism for imparting a step-by-step movement to said carrier and for actuating said slides as they 80 arrive in turn at a given point, and means for suspending the rotation of the carrier in the event of non-explosion of the projected torpedo.

7. In means of the character described, 85 the combination of a carrier, torpedo holders movably mounted thereon, a carrier-actuating member, a holder-actuating member, a gear train serving to actuate said members, and connecting means between the gear train 90 and the holder-actuating member, comprising an electro-magnet and its armature, the electro-magnet being connected with either the gear train or the holder-actuating member and its armature being connected with 95 the other one of said means, for the purpose set forth.

8. In means of the character described, 100 the combination of a carrier, torpedo holders movably mounted thereon, a carrier-actuating member, a holder-actuating member, a gear train serving to actuate said members, and connecting means between the gear train 105 and the holder-actuating member, comprising an electro-magnet and its armature, the electro-magnet being connected with either the gear train or the holder-actuating member and its armature being connected with 110 the other one of said means, and means for positively connecting the magnet and its armature together, for the purpose set forth.

9. In means of the character described, 115 the combination of a carrier, torpedo holders movably mounted thereon, a carrier-actuating member, a holder-actuating member, a gear train serving to actuate said members, a connecting rod joining the gear train to the holder-actuating member and comprising telescoping sections, a magnet connected with one of said telescoping sections and an 120 armature connected with the other of said telescoping sections, and means for controlling the circuit of said magnet.

10. In means of the character described, 125 the combination of a carrier, torpedo holders movably mounted thereon, a carrier-actuating member, a holder-actuating member, a gear train serving to actuate said members, a connecting rod joining the gear train to the holder-actuating member and comprising 130

telescoping sections, a magnet connected with one of said telescoping sections and an armature connected with the other of said telescoping sections, means for controlling the circuit of said magnet, and means for locking said telescoping sections together.

11. In means of the character described, the combination of a carrier, torpedo holders movably mounted thereon, a carrier-actuating member, a holder-actuating member, a gear train serving to actuate said members, a connecting rod joining the gear train to the holder-actuating member and comprising telescoping sections, a magnet connected with one of said telescoping sections and an armature connected with the other of said telescoping sections, a locking pawl serving to lock said telescoping sections together, and means for automatically disengaging the pawl from its locking position when the parts return to the normal position of rest.

12. In means of the character described, the combination of a carrier, a carrier-actuating member, torpedo holders movably mounted on said carrier, a holder-actuating member, a gear train serving to actuate said members, connecting means between the gear train and the holder-actuating member including an electro-magnet and its armature, an electric motor serving to actuate said gear train and having a circuit equipped with a controlling wheel actuated by said gear train and equipped also with a switch, an electro-magnet controlling said switch, and an electric circuit controlling said electro-magnets.

13. In means of the character described, the combination of a carrier, torpedo holders movably mounted thereon, a carrier-actuating member, a holder-actuating member, an electric motor serving to actuate said members, means for automatically starting and stopping the motor, and means for automatically diminishing the supply of current to the motor preparatory to the stopping of the motor.

14. In means of the character described, the combination of a casing, a pivotally-supported plate within said casing, a frame depending from said plate, a rotary carrier supporting said plate, a movable casing-top above said carrier, torpedo holders movably mounted upon said carrier, and actuating means for the carrier and torpedo holders mounted on said frame and adapted to swing out of the casing when said plate is swung upon its pivot, for the purpose set forth.

15. In means of the character described, the combination of a rotary carrier, torpedo holders movably mounted thereon, a carrier-actuating member, a holder-actuating member, a clutch controlling the operation of the carrier-actuating member, a gear through the medium of which the carrier-actuating member is actuated, locking means for said

gear, a gear through the medium of which the holder-actuating member is actuated, means for actuating said last-named gear, and means for releasing the locking means of said first-named gear and actuating said first-named gear for the purpose set forth.

16. The combination with a railway track, of torpedo-placing mechanism comprising a carrier, torpedo holders movably mounted thereon, a carrier-actuating member, a holder-actuating member, and means controlling the movement of said carrier and dependent for its action upon complete retraction of the projected holder, whereby movement is imparted to the carrier only in the event of the explosion of the projected torpedo.

17. In means of the character described, the combination of a carrier, torpedo holders movably mounted thereon, a rock-shaft, means tending normally to turn said rock-shaft, an ejector arm having lost-motion connection with said rock-shaft, and an electro-magnet normally restraining said rock-shaft from moving, for the purpose set forth.

18. In means of the character described, the combination of a carrier, torpedo holders movably mounted thereon, a rock-shaft, a telescopic ejector-actuating arm having lost-motion connection with said rock-shaft, a guide with which the upper end of the ejector arm is connected, and means tending to turn said rock-shaft.

19. In means of the character described, the combination of a carrier, torpedo holders movably mounted thereon, an ejector member, a rock-shaft having lost-motion connection with said ejector member and equipped with means tending to turn the rock-shaft and project a torpedo holder, means at the outer ends of the torpedo holders serving to prevent complete retraction of the torpedo holders in the event of non-explosion of the torpedoes, means normally restraining said rock-shaft from turning, a clutch through the medium of which said carrier is actuated, and clutch-actuating means dependent for its action upon the complete retraction of the projected torpedo holder.

20. In means of the character described, the combination of a casing, a pivotally-supported plate therein, a surmounting carrier, a plurality of torpedo holders movably mounted therein, a holder-actuating member, a carrier-actuating member, and actuating means for said members supported from said plate and including an electric motor having a circuit with terminals applied to a stationary part of the casing, whereby the plate may be swung upon its pivot to raise the mechanism from the casing, for the purpose set forth.

21. In means of the character described, the combination of a carrier, torpedo holders movably mounted thereon, a carrier-actuat-

ing member, a holder-actuating member, a rock-shaft equipped with a weight arm and having lost-motion connection with said holder-actuating member, gear mechanism, 5 a magnet and its armature connected with said gear mechanism and with said rock-shaft, and circuit-controlling means for the circuit of said magnet.

22. The combination with a railway track 10 electrically divided into sections and equipped with a track-switch, and an electric circuit having a branch controlled according to the position of the track-switch, and having a

branch controlled according to the position of the insulated track sections, and torpedo- 15 placing mechanism comprising a carrier, torpedo holders movably mounted thereon, a carrier-actuating member, a holder-actuating member, a gear train, and an electric motor having a circuit controlled by said first- 20 named circuit, for the purpose set forth.

ELLSWORTH E. FLORA.
ROBERT J. ZORGE.
